(57) **CLAIM**

The ornamental design for a motorized mobile system joystick, as shown and described.

DESCRIPTION

FIG. 1 is a top perspective view of a motorized mobile system joystick showing our new design.

FIG. 2 is a bottom perspective view thereof.

FIG. 3 is a front view thereof.

FIG. 4 is a back view thereof.

FIG. 5 is a right side view thereof.

FIG. 6 is a left side view thereof.

FIG. 7 is a top view thereof; and,

FIG. 8 is a bottom view thereof.

The broken lines shown in the Figures show portions of the motorized mobile system joystick that form no part of the claimed design.

The shade lines in the Figures show contour and do not claim surface ornamentation or treatment.
